TOOL FOR CRIMPING ELECTRICAL CONNECTORS OR SIMILAR ARTICLE

Walter Myers Werner, Downingtown, Pa., assignor to
AMP Incorporated, Harrisburg, Pa.

Filed May 11, 1964, Ser. No. 79,905

Term of patent 14 years

(Cl. D54—13)

FIG. 1

FIGURE 1 is a perspective view of a tool for crimping electrical connectors or similar article showing my new design;

FIGURE 2 is a side elevational view of FIGURE 1; and

FIGURE 3 is an end view looking toward the right hand side of FIGURE 2.

The dominant feature of my design resides in the portions shown in full lines.

I claim:

The ornamental design for a tool for crimping electrical connectors or similar article, substantially as shown and described.
